(57) **CLAIM**

The ornamental design for an aroma diffuser, as shown and described.

DESCRIPTION

FIG. 1 is a front view of an ornamental design for an aroma diffuser showing our new design;

FIG. 2 is a rear view of an ornamental design for the aroma diffuser;

FIG. 3 is a left side view of an ornamental design for the aroma diffuser;

FIG. 4 is a right side view of an ornamental design for the aroma diffuser;

FIG. 5 is a plan view of an ornamental design for the aroma diffuser;

FIG. 6 is a bottom view of an ornamental design for the aroma diffuser; and,

FIG. 7 is a perspective view of an ornamental design for the aroma diffuser.

The broken lines in the drawings illustrate portions of the aroma diffuser which form no part of the claimed design.
